[57] CLAIM

The ornamental design for a purse security apparatus, as shown.

DESCRIPTION

FIG. 1 is a front elevational view of a purse security apparatus showing my new design; shown and described separately for clarity of illustration;

FIG. 2 is a rear elevational view thereof;

FIG. 3 is a right side elevational view thereof;

FIG. 4 is a left side elevational view thereof;

FIG. 5 is a top elevational view thereof;

FIG. 6 is a bottom elevational view thereof; and,

FIG. 7 is a perspective view thereof, in an assembled condition. The broken line showing of purse is for illustrative purpose only and forms no part of the claimed design.
